(57) **CLAIM**

The ornamental design for a food storage container, as shown and described.

DESCRIPTION

FIG. 1 is a top, front, right, perspective view of a food storage container showing my design;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a cross-sectional view thereof taken along line 8-8 of FIG. 6; and,

FIG. 9 is an enlarged view of portion 9 in FIG. 8.

The dot-dash broken lines in the drawing views, designating the enlargement areas, depict boundary lines which form no part of the claimed design.
